AVIATOR'S GARMENT

John Raymond Cuthbert Quilter and James
Gregory, Woking, EnglandApplication August 7, 1943, Serial No. 497,796
In Great Britain March 8, 1943

10 Claims. (Cl. 244—143)

This invention relates to parachute harness of the kind combined with aviators' garments, for example by locating a harness between a flying suit and its detachable lining, with the harness attached on the outside of the lining.

The invention has for its main object to provide an improved aviator's garment combined with parachute harness, which can be easily and quickly put on or removed and which can be worn comfortably for long periods without imposing restraint due to tightness of the harness.

Another object of the invention is to provide a loose-fitting garment of this character combined with parachute harness which normally forms a sliding upper vest but can be easily and quickly adjusted to the necessary tightness for safety when the wearer wishes to make a parachute jump.

A further object of the invention is to provide a garment of this character combined with parachute harness located between an outer portion or jacket and an inner portion or lining of the garment, the adjustment to desired tightness of the harness being effected by means external to the jacket portion, and the tension being subsequently releasable by readily accessible means.

A still further object of the invention is to provide an improved aviator's garment adapted for use with a parachute pack of the detached type, the parachute harness being located between an outer jacket portion and an inner portion or lining of the garment, with lift-straps brought out through the jacket portion and fitted with pack-connectors anchored by frangible means on the exterior so as to facilitate the attachment of the parachute pack when the wearer wishes to make a jump.

Other objects and advantages of the invention will hereinafter appear from the subsequent description of a preferred embodiment, given with reference to the accompanying drawings, in which:

Fig. 1 is a front view and Fig. 2 a rear view of the composite garment.

Fig. 3 is a view similar to Fig. 1 but showing the front open and the chest-straps unfastened.

Fig. 4 is a front view and Fig. 5 a rear view, corresponding to Figs. 1 and 2 respectively, but showing the lining of the garment and the harness attached thereto, the outer jacket portion of the garment being removed.

As seen in Figs 1, 2 and 3, the garment comprises an outer portion 10 in the form of a sleeveless jacket, with arm-holes 11 and independent leg-openings 12, all cut wide to fit loosely on the

body, and having a front opening 13 which extends from the neck 14 down to a point near the crotch 15 between the leg-openings 12; the garment also comprises a detachable inner portion or lining 16, partly visible in Fig. 3 and seen more clearly in Figs. 4 and 5, of substantially the same form as the outer jacket portion but of smaller size, the composite garment fitting loosely on the wearer's body.

10 The inner portion or lining 16 is connected to the outer garment or jacket 10 by a sliding clasp fastener 17 (see Fig. 3) of detachable type, running along the adjacent edges 10a and 16a up one side of the front opening 13, around the back of the neck 14, and down the other side of the opening; the adjacent edges of the jacket and lining at the leg-openings 12 may be connected together in front by press-studs or like fasteners 18 at suitable intervals, and at the arm-holes 11 the edges may be connected together by similar fasteners or by buttons and button-holes 18a (see Figs. 4 and 5).

15 The harness, located between the outer jacket portion 10 and the inner portion or lining 16, is attached to the outside of the lining; as seen in Figs. 4 and 5, it comprises lift-straps 19 extending down over the chest and cross-connected by an intermediate portion 19a beneath the seat, a waist-belt 20 having its ends looped around the lift-straps 19, and chest-straps 21 having their ends passed through slits 22 near the front edges 16a of the lining, where they can be secured together by interlocking members 23, of the type requiring relative rotation before they can be separated. The chest-straps 21 include loops 24, through which the lift-straps 19 are passed; they are crossed at the back, as seen in Fig. 5, and brought over the shoulders to carry shackles 25 through which the lift-straps are guided, these shackles being also engaged by loops 26 upon angular braces 27 anchored to the front ends of the chest-straps 21. The several members 20, 21 and 27 of the harness are attached to the lining 16 by stitching as indicated at 20a, 21a and 27a respectively, but the lift-straps 19 are slidable through their guiding loops 20b and 24 and shackles 25: their intermediate connecting portion 19a extending around beneath the seat is also slid able in relation to the lining 16, being loosely guided by enclosure in open-ended hem or patches 28 stitched to the lining at 28a, as seen in Fig. 5.

20 25 30 35 40 45 50 55 Two leg-straps 29, stitched at 29a to the intermediate portion 19a of the lift-straps, pass beneath the crotch by way of a guide piece 15a

55

to the front of the lining, where they are secured to buckles 38 of the non-slip friction type, including for example knurled bars 38a slideable in rectangular buckle-frames; these buckles are engaged by adjustable straps 31, each having one end attached to the lift-strap 18 on the adjacent side by stitching at 31a. The other end of each strap 31 extends from the respective buckle 38 laterally outwards through a slot 32 in the jacket portion of the garment, as seen in Fig. 2, and is fitted with a grip or handle 33 whereby it may be drawn taut by the wearer; thus the leg-loops formed by the intermediate portion 18a of the lift-straps, together with the straps 29 and 31, which are normally left slack to allow freedom, can be readily adjusted to the necessary tightness to ensure that the harness takes the weight comfortably for the wearer when the parachute comes into action. Such adjustment may be effected quickly, that is to say, within one or two seconds, by pulling or jerking the two projecting ends of the straps 31 in opposite directions laterally of the aviator's body, one grip or handle 33 being taken in each hand so that they can be operated simultaneously in a minimum time.

After the straps 31 have been pulled or jerked to tighten the leg-loops, the grips 33 can be released, the slideable friction bars 38a then locking the straps 31 in the adjusted position; but if the wearer does not have to jump, the straps 31 can be subsequently released by undoing a few of the press-studs or like fasteners 18 at the front of the leg-openings 12, and manipulating the buckles 38 to free the straps 31, whereupon the waistbelt and chest-straps will be loosened automatically.

The front opening 13 of the garment is normally closed by a sliding clasp fastener 34, as seen in Fig. 1; this fastener can be pulled down so as to free the edges 13a of the opening from the top almost down to the crotch 15, as seen in Fig. 3. As soon as the front of the garment is opened in this way, the interlocking members 28 become accessible for separation, so that the wearer can put on or remove the complete garment; the leg-openings 12 will be sufficiently roomy for passage of the feet, provided that the adjusting straps 31 of the leg-loops are in loose condition. The sliding clasp fastener 34 is preferably arranged to pass beyond the line of tension between the edges 13a at the top of the front opening in the closed position by providing tab-extensions 35 at the top of the stringers.

The composite jacket or garment is most conveniently employed with a parachute pack of the detached type, the lift-straps 18 of the harness being brought out through the jacket by way of slits 36 near the shoulders (see Fig. 1) and having their pack-connector hooks or the like 37 anchored by frangible means at convenient points on the exterior, for example at 38 (see Fig. 1), these points being level with and on either side of the chest-strap interlocking members 28. The connector hooks 37 and the external lengths of the lift-straps 18 will be preferably covered by flaps 39 and 40 respectively with press-stud fasteners 41; the flaps 39 over the connector hooks can be quickly released by pulling away their tabs 42 when the parachute pack is to be connected, and the fasteners of the other flaps 39 will readily yield to the pull of the lift-straps 18 when the parachute comes into operation.

In other respects, the composite jacket may

resemble the garment described and illustrated in our prior patent specification No. 2,256,597, the harness being located upon the lining so that the top half forms a sliding upper waistcoat of cross bracing and chest-straps all in one, giving maximum comfort until the moment of action.

The outer jacket portion will also be provided with the customary pockets 43, as well as as fittings 44 and 45 for an inflatable life-belt, and for other necessary purposes.

What we claim is:

1. An aviator's garment combined with parachute harness, comprising a loose-fitting jacket having two wide and independent leg-openings and adapted to open down the front to a point near the crotch, a detachable lining for said jacket, and harness located between said jacket and lining, said harness being normally slideable in relation to the aviator's body and including lift-straps extending out through said jacket, chest-straps slidably connected to said lift-straps, separable means for connecting adjacent ends of said chest-straps near the front opening 15 of said jacket, a waist-belt having its forward ends slidably connected to said lift-straps, and quickly adjustable leg-loops around said leg-openings, said leg-loops being connected to said lift-straps and having free ends extending out through said jacket to within reach of the aviator's hands for effecting the quick adjustment of said leg-loops.

2. An aviator's garment combined with parachute harness, comprising a loose-fitting sleeveless jacket having two wide and independent leg-openings and adapted to open down the front to a point near the crotch, and harness located inside said jacket, said harness including lift-straps connected together beneath the seat and extending upwardly at the sides and over the chest to pass slidably out through said jacket and adjustable leg-loops around said leg-openings, said leg-loops being formed by the intermediate seat-portion of said lift-straps, leg-straps secured to said intermediate seat-portion, adjusting straps secured to the upwardly extending side portions of said lift-straps, and quick-action buckles engaging said leg-straps with said adjusting straps, said adjusting straps passing from said buckles to the exterior of said jacket for manual operation to tighten said leg-loops.

3. An aviator's garment combined with parachute harness, comprising a jacket fitting loosely on the wearer's body and hanging from the shoulders, said jacket having wide arm-holes and leg-openings and being adapted to open down the front to a point near the crotch, and harness located inside said jacket, said harness including lift-straps extending out through said jacket, at least one strap extending partly around the aviator's body, and quickly adjustable leg-loops extending around said leg openings said leg-loops being connected to said lift-straps and having ends extending out through said jacket to within reach of the aviator's hands for effecting the quick adjustment of said leg-loops, said leg-loops being normally left slack to allow freedom of said leg-openings but being manually adjustable from the exterior of said jacket so as to tighten around the wearer's legs, and the tensioning of said lift-straps by operation of the parachute after adjustment of said leg-loops causing the tensioning of said strap extending partly around the aviator's body.

4. An aviator's garment combined with parachute harness, comprising a loose-fitting jacket having two wide and independent leg-openings and adapted to open down the front to a point near the crotch, a detachable lining for said jacket, harness located between said jacket and lining, said harness being normally slideable in relation to the aviator's body and including quickly adjustable leg-loops extending around said leg-openings and lift-straps extending out through said jacket, and means for tightening said leg-loops before bringing the parachute into operation, said tightening means including handles adapted for movement in opposite directions laterally from the aviator's body.

5. An aviator's garment combined with parachute harness, comprising a loose-fitting jacket having two wide and independent leg-openings and adapted to open down the front to a point near the crotch, and harness located inside said jacket, said harness forming a slideable vest with attached leg-loops normally extending loosely around said leg-openings, each of said leg-loops including strap-portions connected by a friction-grip adjuster device and having a strap-end projecting through said jacket for manual adjustment of the respective leg-loop to desired tightness for taking part of the weight of the aviator when the parachute subsequently comes into operation.

6. An aviator's garment combined with parachute harness, comprising a loose-fitting jacket having two wide and independent leg-openings and adapted to open down the front to a point near the crotch and harness located inside said jacket, said harness forming a slideable vest with attached leg-loops normally extending loosely around said leg-openings, each of said leg-loops including strap-portions connected by a friction-grip adjuster device and having a strap-end projecting through said jacket, the two projecting strap-ends being operable simultaneously by pulling in opposite directions laterally from the aviator's body for quick tensioning of said leg-loops to desired tightness for taking part of the weight of the aviator when the parachute subsequently comes into operation.

7. An aviator's garment combined with parachute harness, comprising a loose-fitting jacket, harness located inside said jacket, said harness forming a slideable vest with attached leg loops normally slack but adapted when tightened to take the major part of the aviator's weight during descent by parachute, and means for quickly adjusting said leg-loops to desired tightness independently of the remainder of said harness, said quick adjusting means including friction-grip adjusters interposed in said leg-loops and adjusting straps extending from said adjusters to the exterior of said jacket for manual tensioning of said leg-loops by the aviator.

8. An aviator's garment combined with parachute harness, comprising a loose-fitting jacket,

a detachable lining for said jacket, and harness located between said jacket and lining, said harness being partly slideable in relation to said lining, the slideable part of said harness including lift-straps connected together beneath the seat and leg-loops normally fitting loosely around the thighs, said lift-straps extending upwardly at the sides, and over the wearer's chest to pass slidably out through said jacket, and said leg-loops including leg-straps connected to the intermediate seat-portion of said lift-straps, friction-grip adjusters connected to said leg-straps, and adjusting straps connected at one of their ends to the upwardly extending side portions of said lift-straps, said adjusting straps being engaged by said adjusters and having their free ends projecting to the exterior of said jacket for manual tensioning of said leg loops by the aviator.

9. An aviator's garment combined with parachute harness, comprising a loose-fitting jacket having two wide and independent leg-openings, a detachable lining for said jacket, and harness located between said jacket and lining, said harness including lift-straps connected together beneath the seat and leg-loops around said leg-openings, said lift-straps extending upwardly at the sides to pass slidably out through said jacket, and said leg-loops including leg-straps connected to the intermediate seat-portion of said lift-straps and slideable in relation to said lining, friction-grip adjusters connected to said leg-straps, and adjusting straps connected at one of their ends to the upwardly extending side portions of said lift-straps, said adjusting straps being engaged by said adjusters and having their free ends projecting to the exterior of said jacket for manual tensioning of said leg-loops by the aviator.

10. An aviator's garment combined with parachute harness, comprising a loose-fitting jacket having two wide and independent leg-openings, a detachable lining for said jacket, and harness located between said jacket and lining, said harness including lift-straps connected together beneath the seat and leg-loops around said leg-openings, means for guiding the intermediate seat-portion of said lift-straps in slideable relation to said lining, said lift-straps extending upwardly at the sides to pass slidably out through said jacket, and said leg-loops including leg-straps connected to the intermediate seat-portion of said lift-straps and slideable in relation to said lining, friction grip adjusters connected to said leg-straps, and adjusting straps connected at one of their ends to the upwardly extending side portions of said lift-straps, said adjusting straps being engaged by said adjusters and having their free ends projecting to the exterior of said jacket for manual tensioning of said leg-loops by the aviator, and said adjusters being accessible from the exterior of said jacket for releasing the tension of said adjusting straps.

JOHN RAYMOND CUTHBERT QUILTER.
JAMES GREGORY.
